US00D998068S

(12) **United States Design Patent** (10) **Patent No.:** **US D998,068 S**
(45) **Date of Patent:** **** Sep. 5, 2023**

(54) **ABDOMINAL EXERCISE WHEEL**

(71) Applicant: **Bala Bangles, Inc.**, Los Angeles, CA (US)

(72) Inventors: **Natalie N. Holloway**, Glendale, CA (US); **Maximilian C. Kislevitz**, Glendale, CA (US)

(73) Assignee: **Bala Bangles, Inc.**, Los Angeles, CA (US)

(**) Term: **15 Years**

(21) Appl. No.: **29/818,155**

(22) Filed: **Dec. 7, 2021**

(51) LOC (14) Cl. **21-02**

(52) U.S. Cl.

(57) **CLAIM**

The ornamental design for an abdominal exercise wheel, as shown and described.

DESCRIPTION

FIG. 1 is a top, left perspective view of an abdominal exercise wheel, showing our new design in use;

FIG. 2 is a top, left perspective view of an abdominal exercise wheel, showing our new design in use;

FIG. 3 is a top, front left perspective view of an abdominal exercise wheel, showing our new design;

FIG. 4 is a bottom, rear right perspective view of the abdominal exercise wheel of FIG. 3;

FIG. 5 is a top plan view of the abdominal exercise wheel of FIG. 3;

FIG. 6 is a bottom plan elevation view of the abdominal exercise wheel of FIG. 3;

FIG. 7 is a front side elevation view of the abdominal exercise wheel of FIG. 3;

FIG. 8 is a rear side elevation view of the abdominal exercise wheel of FIG. 3;

FIG. 9 is a left side elevation view of the abdominal exercise wheel of FIG. 3; and,

FIG. 10 is a right side elevation view of the abdominal exercise wheel of FIG. 3.

The broken lines in the drawings show the environment and form no part of the claimed design.

1 Claim, 7 Drawing Sheets
